UNITED STATES PATENT OFFICE.

JOHN F. POWELL, OF MONROE, LOUISIANA.

PORTRABLE COMBINATION WOODWORKING MACHINE.

1,417,686.

Specification of Letters Patent. Patented May 30, 1922.

Application filed August 1, 1921. Serial No. 488,970.

To all whom it may concern:

Be it known that I, JOHN F. POWELL, a citizen of the United States, residing at Monroe, in the parish of Ouachita, State of Louisiana, have invented certain new and useful Improvements in Portable Combination Woodworking Machines; and I do hereby declare the following to be a full, clear, and exact description of the invention, such as will enable others skilled in the art to which it appertains to make and use the same.

This invention relates to a portable combination wood working machine designed primarily for use in connection with building operations and adapted to be moved as may be required from place to place for the convenience of the operative, the purpose being to arrange in compact form a plurality of mechanisms or units adapted respectively for planing, dressing, mortising and boring, cross cutting, plowing, dadoing, molding, ripping, jointing and like functions incident to the preparation of lumber for use in building operations, all arranged and adapted for selective connection with a common motor or source of power preferably carried by the machine as a component part thereof, and with the several units so relatively disposed in the combination as to minimize the amount of time required in handling the lumber and in transferring elements thereof from unit to unit where successive operations are required in the preparation of the same for use in the projected building or structural object; and with these general aims in view the invention consists in a construction, combination and relation of parts of which a typical embodiment is illustrated in the accompanying drawings therein.

Figure 1 is an elevation in a side view of the apparatus.

Figure 2 is a plan view of the same.

Figure 3 is a view from the opposite side to that indicated in Figure 1.

Figures 4 and 5 are respectively front and rear views.

Figure 6 is a section or plane indicated by line 6—6 of Figure 1.

Figures 7 and 8 are respectively plane and edge views partly in section of the side unit designed for ripping, angle-cutting and panel raising.

The apparatus embodies essentially a base, preferably wheel supported as indicated at 11 to provide for transportation with facil-

ity from place to place, it being the intention to remove the supporting wheels or equivalent elements when the apparatus reaches a station at which it is to be used to permit of substantially seating the base upon the surface of the ground or similar horizontal support to the end that the tables of the several working units may be bench-high for the convenience of the operators, and supported by the base in a super-structure embodying primarily a central or intermediate tower 12 having uprights 13 in front and in rear of which are arranged standards 14 and 15 respectively connected with the tower by suitable reinforcing elements such as the braces 16 and 17, a mid high platform 18 being extended forwardly from the tower to the forward standards 14 for the purpose of supporting a motor 19, together with wood working units designed specifically for different purposes arranged within the tower and extensions of the super-structure and upon the end portions of the base beyond the said super-structure and adapted by their positions to be accessible respectively at one or more sides according to the purposes of such units and the character and ordinary dimensions of the structural articles which are treated thereon. The base is preferably of an elongated form so as to provide for disposing the several units in what may be termed for convenience a longitudinal series so that those required ordinarily to operate upon timbers or objects of considerable length may be accessible from both sides of the base to permit of the timber projecting at its extremities laterally beyond the area of said base.

In the illustrated embodiment of the invention the tower 12 is employed as a support for a swing cut-off operating transversely of the length of the platform or base and having a pendulum frame 20 supported for oscillatory movement upon a shaft 21 which receives its rotary movement from a longitudinal counter or transmission shaft 21^a through the belt 21^b, and which in turn receives motion from a transverse main shaft 22 operatively connected as by means of a belt 23 with the motor 19,—a second longitudinal counter or transmission shaft 24 being arranged near the plane of the base of the apparatus and being connected with counter shaft 21^a by a belt 24^a, so that the two counter shafts extending respectively forwardly and rearwardly from the

main shaft or the vertical plane of the main shaft are disposed respectively in an over-head position as the shaft 21^a and a position adjacent to the plane of the base, as the shaft 24, to minimize tendency thereof to interfere with the movements of the operators and the handling of material with reference to the several wood working units. The swing cut-off is provided with a saw 25 operating in relation to a suitable table 26 and having its arbor 27 connected with the over-head shaft 21 by means of belt 28 or its equivalent traversing the pulleys 29 and 30.

The platform 18 by which the motor is supported and above which are arranged the means for communicating motion from the motor to the main drive shaft 22 is arranged in an over-head position preferably slightly above the mid height of the super-structure embodying the tower 12, and beneath said platform is conveniently arranged the planer 31 which may be of any ordinary or conventional construction, deriving its power from the lower counter shaft 24 with its carriage movable transversely of the base so as to be accessible at its ends from opposite sides of the base without requiring that the operator occupy a position in the way of any other operative units of the apparatus and without involving any interference in the operation of the planer with any of the other units.

Arranged for convenience upon the rearward extension of the super-structure or frame work at one side of the base is the mortising and boring unit 32 (shown simply as a boring unit) and transversely opposite thereto at the other side of the base there is arranged the rip, angle cut-off and panel raising unit 33 of which the table 34 is disposed longitudinally of the base and projects laterally beyond the same as does the table 26 of the swing cut-off which is disposed at the opposite side of the base, and the table 36 of the mortising and the boring unit, it being noted, however, that the platform 36 of the mortising and boring unit is arranged in a plane above the table 26 of the swing cut-off, so that timbers resting upon the table 26 for transverse severance by the swing cut-off may extend under the table 36 of the mortising and boring apparatus without interfering with the operation of either and permitting of the use of both units at the same time.

Carried by the terminal portions of the base in front and in rear of the super-structure frame, as above indicated, are the units which require access at opposite ends of their tables and also at one side thereof, and hence in the illustrated embodiment of the invention the unit which is arranged at the front end of the base is a dado and cut-off mechanism having a table 37 with the dado head 38 carried by an arbor 39 which re-

ceives its motion from an overhead counter-shaft 21^a through an intermediate shaft 40, to and from which motion is communicated by the belts 41 and 42 arranged so as to permit free access to all parts of the table 70 in the manipulation of the lumber, and in addition to the table being accessible as above noted at both ends, which are located respectively at the sides of the base, it is accessible from the side at which, as in the 75 ordinary construction, there is arranged a sliding extension 43 designed to increase the working area thereof when required. At the other or rear end of the base are arranged two units, one indicated at 44 which is de- 80 signed for plow, dado and molding work and the other shown at 45 which serves as a jointer, each of said units being accessible at its ends, that is from both sides of the base, and each unit also being accessible 85 from one side, the unit 44 from the inner side as provided for by the intervening space 46 between the same and the adjacent end of the rip and angle cut-off unit 33, and the other from the rear end of the base. 90 The two tool arbors 47 and 48 of the units 44 and 45 receive motion from the rearwardly extended counter-shaft 24 which in the space 46 at the inner side of the unit 44 extends through a suitable housing 49 so 95 that the feet of the operator may not be exposed to the movements thereof when the machine is in operation.

The several units may, as will be obvious, be constructed along any suitable or pre- 100 ferred conventional lines or may have special features adapting them for particular lines of work and may as shown be equipped with extension, folding, hinged and otherwise adjustable tables actuatable, for ex- 105 ample, as illustrated in connection with the units 44 and 45, by hand screws 50 and 51, and in addition into the side unit 33, de- 110 signed as above indicated for use as a rip angle cut-off and panel raiser, the table 34 being hinged as indicated at 52 and adjustable by the hand screw 53, may have an adjustable stop 54 for guiding the material in relation to the rip saw 55 carried by the arbor 56, as shown in Figures 1 to 5 inclusive, 115 and inter-changeably therewith may be provided with the angle cut-off mechanism 57 illustrated in Figures 7 and 8 carried by a movable table 59 mounted upon suitable tracks or guides 60 and equipped with the 120 usual quadrant 61 for determining the angle of the guide in making a cut-off for jointing or like purpose.

What is claimed is.

1. A wood working machine having a 125 portable frame embodying a horizontal base, bench high tables supported thereby and a super structure including a motor supporting platform arranged above the plane of the tables, a main drive shaft disposed trans- 130

versely substantially in the plane of the platform for direct connection with a motor thereon, forwardly and rearwardly extending longitudinal counter-shafts disposed respectively above the plane of the platform and adjacent to the plane of the base and operatively connected with the main shaft, and wood working implements disposed at the ends and sides of the frame and having 5 10 15 20 25

tool carriers for selective connection respectively with said counter-shaft.

2. A wood working machine having a portable frame embodying a horizontal base, bench high tables supported thereby and a 15 20 25 30 super-structure including a motor supporting platform arranged above the plane of the tables, a main drive shaft disposed transversely substantially in the plane of the platform for direct connection with a motor thereon, forwardly and rearwardly extending longitudinal counter-shafts disposed respectively above the plane of the platform and adjacent to the plane of the base and operatively connected with the main shaft, and wood working implements disposed at the ends and sides of the frame and having tool carriers for selective connection respectively with said counter-shaft. Said wood working implements including a planer having its table movable transversely beneath said platform.

3. A wood working machine having a portable frame embodying a horizontal base, bench high tables supported thereby and a 35 40 45 50 55 super-structure including a motor supporting platform arranged above the plane of the tables, a main drive shaft disposed transversely substantially in the plane of the platform for direct connection with a motor thereon, forwardly and rearwardly extending longitudinal counter-shafts disposed respectively above the plane of the platform and adjacent to the plane of the base and operatively connected with the main shaft, and wood working implements disposed at the ends and sides of the frame and having tool carriers for selective connection respectively with said counter-shaft, said wood working implements including a planer having its table movable transversely beneath said platform and a swing cut-off provided with a frame pivotally supported above the plane of the platform for transverse swinging movement in rear of the plane of the platform and the subjacent planer.

4. A portable combination wood working machine having a wheel supported base of elongated form having a super-structure consisting of a tower and forwardly and rearwardly projecting extensions of which the former includes an elevated platform, wood working units disposed at opposite ends of the base and having bench high tables below the plane of said platform, a

motor carried by the platform, a transverse main shaft located in rear of the tower and operatively connected with the motor, forwardly and rearwardly extending longitudinal counter-shafts arranged respectively at the top and bottom of the tower and operatively connected with the main shaft, and means for selectively connecting the said units to said counter-shaft.

5. A portable combination wood working machine having a wheel supported base of elongated form carrying an intermediate super-structure consisting of a tower having a forwardly projecting platform for supporting a motor, a transversely operating swing cut-off mounted in the tower, a transverse main shaft mounted in rear of the tower and operatively connected with the motor, forwardly and rearwardly extending over head and underfoot countershafts operatively connected with the main shaft, the swing cut-off being operatively connected with the over head counter shaft, a planer arranged upon the base beneath the platform which supports the motor and operatively connected with the underfoot counter shaft, and other wood working units mounted upon the base respectively in front and in rear of the super-structure and having their operative elements adapted to be selectively connected respectively with said over head and underfoot counter shafts.

6. A portable combination wood working machine having a wheel supported base of elongated form carrying an intermediate super-structure consisting of a tower having a forwardly projecting platform for supporting a motor, a transversely operating swing cut-off mounted in the tower, a transverse main shaft mounted in rear of the tower and operatively connected with the motor, forwardly and rearwardly extending over head and underfoot counter shafts operatively connected with the main shaft, the swing cut-off being operatively connected with the over head counter shaft, a planer arranged upon the base beneath the platform which supports the motor and operatively connected with the underfoot countershaft, and other wood working units mounted upon the base respectively in front and in rear of the super-structure and having their operative elements adapted to be selectively connected respectively with said over head and underfoot counter shafts, each of said terminally positioned units being accessible at three sides for the manipulation of work in connection therewith.

In testimony whereof, I affix my signature, in the presence of two witnesses.
